UNITED STATES PATENT OFFICE.

VINCENT V. VEENSCHOTEN, OF ERIE, PENNSYLVANIA, ASSIGNOR TO NORTHERN EQUIPMENT COMPANY, OF ERIE, PENNSYLVANIA.

CHAIN GRATE.

1,401,211.

Specification of Letters Patent. Patented Dec. 27, 1921.

Application filed September 20, 1919. Serial No. 325,189.

To all whom it may concern:

Be it known that I, VINCENT V. VEENSCHOTEN, a citizen of the United States, residing at Erie, in the county of Erie and State of Pennsylvania, have invented certain new and useful Improvements in Chain Grates, of which the following is a specification.

This invention relates to improvements in chain grates, and particularly that type of grate or stoker which is known in the trade as the Coxe stoker. The invention has for its object providing means for replacing certain parts of the grate when they become broken or defective. It has been found that the present method of replacing the parts requires so much time that it is usually necessary either to stop the operation of the grate or to remove large parts thereof and keep on hand reserve parts in order to replace the broken or injured elements, and my invention provides means for obviating this delay and trouble.

Of the accompanying drawings Figure 1 is an end view of a portion of a chain grate which embodies the features of my invention. Fig. 2 is an enlarged end view of one of the bars of the grate. Fig. 3 is a side elevation of a portion of the bar with some of the elements thereof removed. Fig. 4 is a plan view of the portion of the bar shown in Fig. 3. Fig. 5 is an elevation of one of the units or keys which are to be replaced when broken.

The chain grate is composed of a series of grate bars 5 fixed at each end in a suitable manner to a chain 6, which is operated by the sprocket wheel 7 suitably mounted and driven. As is well understood the bars of the grate are by these means carried under the fire bed of the furnace and form a suitable support therefor in an ordinary manner. Each of the bars of the grate is composed of a body portion 8 upon which is mounted securing ribs 10 and a series of keys 9. These keys, while fitting fairly snugly together, are sufficiently spaced apart to allow air to pass up, or be forced up, from below into the fire bed above. The keys are slidably mounted on securing ribs 10; these ribs extending substantially the full length of the bar, and the keys having suitable recesses 11 therein by means of which they are mounted on the ribs. The ends of the grate bars comprise heads 12,

and it is common to have a portion of the ribs at one end, adjacent the head 12, removable, by suitable means, so that in case of a fracture or injury to any of the keys this portion of the rib may be removed, together with the first key, and other keys may be removed by sliding them along the ribs to the end thereof until the broken key is reached and removed and replaced. The keys are then replaced and the removable portions of the ends of the ribs are also replaced together with the first key. It is difficult, however, to remove the rib ends for various reasons, partly because fastening means have been used which require the operator to work on the inner side of the sprocket wheel 7; hence necessitating stopping the grate. To avoid this it has been customary to remove the entire bar from the chain and replace it by another assembled reserve bar, as this can be done while the grate is in operation, it being understood that the rate of movement of the grate is so slow that the end bars will be exposed for several minutes.

To avoid the necessity of having a reserve bar and replacing the entire bar, I provide a removable filler member 14 which is adjacent the ends 13 of the ribs and connect the same to the head by suitable means extending outwardly to the end of the bar. I prefer for this connecting purpose a bolt 15, which passes through the head 12 and is screwed into the member 14, the head of the bolt passing into a recess 16 in the head 12. By this arrangement it is necessary, in order to remove one of the keys, only to remove the bolt 15 and then the member 14, and the keys may be slipped off of the ends of the ribs. It is thus not necessary to work on the inner side of the wheel 7. To replace a broken key, it is necessary only to remove such key, to remove the bolt 15 and filler member 14, to insert a new key at the ends of the ribs, and by forcing the same into operative position thereon, to slide the intervening keys along the ribs to fill the gap without stopping the operation of the grate or without removing the entire bar. The bar is connected to the chain 6 by means of a pin 18 passing through the chain link and also through a hole 19 in the lug 17, fixed to the head.

I claim as my invention:

A grate bar comprising a body portion, a

head mounted on one end of said body portion, and longitudinal securing ribs mounted on said body portion, in combination with a plurality of fuel supporting keys slidably secured on said ribs, a filler member mounted between said head and the adjacent ends of said ribs, and a bolt pass-

ing through said head and screwed into said member, the space between the said head and the ends of said ribs being greater than 10 the width of each of said keys.

In testimony whereof, I hereunto set my hand.

VINCENT V. VEENSCHOTEN.
